Primary Examiner—Elizabeth A Albert*Assistant Examiner*—Karen E Eldridge Powers(74) *Attorney, Agent, or Firm*—Fellers, Snider, Blankenship, Bailey & Tippens, P.C.(57) **CLAIM**

The ornamental design for a gore-shaped cooling pack, as shown and described.

DESCRIPTION

FIG. 1 is a perspective view of a gore-shaped cooling pack according to the first embodiment of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the gore-shaped cooling pack according to my new design, in which the thick, long-short-long broken line illustrates the point of insertion of the claimed design into a pocket formed in a gore of a cap and forms no part of the claimed design; and,

FIG. 9 is a perspective view of a cap having a gore-shaped cooling pack in a crown portion thereof.

The broken line showing of a hat in FIGS. 8 and 9, respectively, are for the purpose of illustrating the environment in which the design is associated and forms no part of the claimed design.
